UNITED STATES PATENT OFFICE.

RICHARD CLAYTON FRASER, OF CENTRAL CITY, COLORADO, ASSIGNOR OF ONE-THIRD
TO WILLIAM R. FRASER, OF DURANGO, COLORADO.

ROTARY ENGINE.

1,258,552.

Specification of Letters Patent.

Patented Mar. 5, 1918.

Application filed May 9, 1917. Serial No. 167,532.

To all whom it may concern:

Be it known that I, RICHARD CLAYTON FRASER, a citizen of the United States, residing at Central City, in the county of Gilpin and State of Colorado, have invented certain new and useful Improvements in Rotary Engines; and I do hereby declare the following to be a full, clear, and exact description of the invention, such as will enable others skilled in the art to which it appertains to make and use the same.

This invention relates to rotary steam engines, and more particularly to a rotary steam engine having compound steam chambers.

It is one of the objects of the present invention to provide a compact, simple engine, and a further object of the invention is to provide a rotor having a series of pockets in which steam under full boiler pressure may be utilized initially in a series of high pressure pockets, and then subsequently the steam is transferred from these pockets into expansion chambers which may be suitably arranged upon the rotor, the several chambers or pockets in the rotor of the engine being co-operatively disposed with relation to complementary steam chambers or pockets in the casing of the engine.

It is another object of the present invention to provide an engine of such construction that it may be arranged or installed directly upon the machine or apparatus which is to be driven, as, for instance, in combination with a machine tool, or for driving purposes in vehicles, or may be utilized as a stationary engine when arranged upon a suitable support.

It is another object of the invention to provide a compound, rotary and reversible steam engine, and one in which friction is eliminated as much as possible and in which means are provided to pack the running parts at the joints of the respective elements of the motor so as to conserve the pressure of the steam.

Another and important object of the present invention is to provide a rotary, compound and reversible steam engine in which the parts may be readily mounted and dismounted for the purpose of providing for renewal or repairs, and to enable ready access to the various portions of the motor.

With these and other objects in view as will be rendered manifest in the following

specification, one embodiment of my invention is illustrated in the accompanying drawings, in which:

Figure 1 is a side elevation, partly in section, showing the end of the engine which is provided with a set of mechanically operated D valves.

Fig. 2 is a vertical, central section, longitudinally of the engine.

Fig. 3 is a detail view of the end plate of the engine showing the steam chest of the D valves and the plate being partly broken away to indicate the position of the steam pockets.

Fig. 4 is a view of the engine casing with the end plate removed, and showing the relation of the steam pockets and the rotor within the casing from the same side of the engine illustrated in Fig. 3, and omitting the end plate thereof.

Fig. 5 is a side elevation of the organized engine.

Fig. 6 is a detail view of the end plate showing the series of ducts and steam ports coördinate with a set of steam actuated piston valves, the latter being omitted from this figure.

Fig. 7 is an end elevation of the end plate shown in Fig. 6 and illustrating in sectional detail the piston valves and their steam connection.

Fig. 8 is a horizontal section on line 8—8 of Fig. 7, showing the piston valve in one of its positions, and

Fig. 9 is an end elevation of the engine looking toward the right hand side of the engine in Fig. 5, showing the cap removed and illustrating the rotor and the casing partly in section to show the relation of the steam pockets thereto.

In the present embodiment of my invention it is shown as designed as a stationary engine provided with a suitable bearing or framework 2 which is adaptable to be appropriately secured to a foundation or support in the usual or ordinary manner, although it is to be understood that the co-operative driving mechanisms of this engine may be utilized in direct combination with apparatus to be driven, such, for instance, as any machine tool or line shaft or vehicle transmission, if so desired. Journaled upon the uprights of the frame 2 there is shown a suitable shaft 3 which is provided with a rotor or rotary piston member 4 prefer-

ably keyed as at 5 upon the shaft 3. The periphery of the rotor is suitably incased or inclosed in a cylindrical casing 6, and the opposite ends of the casing 6 on each side 5 of the rotor 5 are provided with suitable end plates 7 and 8, which may be bolted or otherwise appropriately connected to the casing or cylinder ring 6.

It is one of the important features of my 10 present invention to provide a rotary steam engine in which motive fluid force may be utilized first at initially high pressure directly from a source of supply, and then subsequently exhausted from the high pressure 15 sure pockets or chambers to other and compound chambers. To that end the rotor 4 is provided with a series of pockets 10, illustrated in Fig. 4, these being peripherally disposed about the circumference of the rotor 20 and preferably are of triangular longitudinal cross sectional form and provided at one end with an inclined wall 10' against which steam is adapted to impinge during the operation of the engine. These pockets 25 10 form the compound chambers of the engine and are adapted to move successively into opposition to complementary compound steam pockets 11 of which there is one each at the top and at the bottom of the 30 engine cylinder 6. The high pressure pockets or chambers in the rotor 4 are shown as arranged in the end face of the rotor in Fig. 4 at 12, there being in this instance shown four of the peripheral compound 35 pockets 10 and four of the high pressure pockets 12 arranged in the side of the engine. It is one of the features of the invention to provide a reversible compound fluid pressure operated engine, and to obtain 40 this system of operation the rotor preferably is constructed with two series of the compound pockets 10, as illustrated in Fig. 2, and also with two series of the pockets 12 in the opposite end walls of the rotor 4, as illustrated in dotted lines in Fig. 2. The 45 reverse driving operation of the rotor 4 is secured by reversing the direction of the pitch or inclination of the abutment walls 10' and 12' respectively of the pockets 10 and 12 so that when steam is admitted, for instance to the pockets 10 and 12, Fig. 4, the 50 engine will be driven left hand, and conversely when the steam or other fluid pressure is admitted to the pockets on the other side of the engine, these pockets being directed in a reverse direction, cause the rotation of the rotary member in an opposite or clockwise direction.

While suitable means may be provided to 60 control the flow of the fluid pressure or steam into the initial or high pressure pockets 12, and then subsequently into the compound pockets 10, I have shown in the present embodiment of the invention two different systems of valve mechanisms for accom-

plishing this control of flow, and, as clearly illustrated in Fig. 2, end plate 7 of the engine is shown as provided with diametrically opposite and aligned upper and lower steam chests 13 and 14, and within these 70 chests there are slidably mounted suitable types of valves, for instance, the well known D valves 13' and 14', these being connected together through means of the piston rod or connecting link 15 which is provided with 75 a central slotted portion at 15' to straddle the shaft 3. To secure the proper timing and movement of the valves 13' and 14' the connecting rod 15 is suitably actuated by appropriate connecting means with the shaft 80 3. In this form of engine the connecting rod 15 is provided with a stem 16 which may carry an anti-friction roller 16'—this adapted to operate in an internal cam 17 keyed or otherwise suitably secured to the 85 shaft 3.

Steam is supplied to the several valves of the engine through means of a steam main 20, Fig. 5, which may be provided with a throttle or cut-off valve 21 and is 90 branched as at 22 and 22' to provide respective connections to the opposite end plates of the engine, branch 22 being provided with a valve 23 which in turn is connected with a branched pipe 24, Fig. 1, leading to the upper and lower steam chests 13 and 14 respectively. The D valves in these 95 chests are adapted to open and close respective steam passageways leading through the end plate 7 to the steam chambers 12 100 and 10. As shown in Figs. 2 and 3 the steam chests 13 and 14 are provided with outermost ducts or passageways 13^a and 14^a respectively which lead inwardly and discharge into respective pockets 13^b and 14^b 105 formed on the inner surface of the end plate 7 in a circle in which the high pressure pockets 12 of the adjacent face of the rotor 4 are provided. Next adjacent and inwardly from the mouths of the ports 13^a and 14^a there are provided steam passageways 13^c and 14^c, these being directed through the end plate 7 transversely and thence outwardly, as shown in Fig. 2, to communicate with corresponding ducts 115 formed in the casing 6, and leading into the outer compound steam pockets 11. Below the mouths of the passageways 13^c and 14^c and nearer the center of the plate there are further provided another set of high pressure steam ports or passageways 13^d and 14^d, these being directed through the end plate 7 angularly across the same as shown 120 in Fig. 3 to communicate with respective pockets 13^e and 14^e which also are disposed in the circle coördinate with the circle in which the high pressure pockets 12 in the adjacent face of the rotor operate. Thus 125 there is provided in each steam chest 13 and 14 a series of three ports, for instance in the 130

chest 13 ports 13^a, 13^c and 13^d. When the valve 13' is actuated through means of the cam 17 to the position shown in Fig. 2, live steam or other fluid pressure is permitted 5 to pass through the innermost port 13^d, and thence into the connected pocket 13^e which will therefore be charged with steam under full pressure, and as the rotor 4 rotates it will bring one of its pockets 12 adjacent 10 to the pocket 13^e and pressure will be permitted to enter the pocket 12 and impinge upon the abutment surface or wall 12' of the latter and cause, the rotor to turn. While D valve 13' is in its uppermost position, communication is also established at 15 this time between the pocket which is connected to the uppermost port 13^a, Fig. 3, and the valve 13' is provided in its bottom surface with a recessed portion which permits the flow of steam from the steam port 13^a into the steam port 13^c, thus exhausting one of the rotor pockets 12 through the contiguous pocket in the end face, and through the port 13^c, thus allowing the steam to 20 expand through the last port and pass into the peripheral pocket 11 so that when a peripheral pocket 10 of the rotor moves into juxtaposition thereto the steam is further expanded and its force utilized on the periphery of the rotor to rotate the latter. In a similar manner control of the steam is to be through the lower D valve 14', this being shown in Fig. 3 in its upper position and uncovering the port 14^a to permit high 25 pressure steam to pass thereto and into the end wall pocket 14^c to supply steam to a pocket in the adjacent face of the rotor. Meanwhile the steam is exhausting from one of the pockets, at 14^b, through the steam 30 passageway 14^d, and beneath the valve 14' thence outwardly through the steam passageway 14^e to the peripheral pocket shown in the lower portion of Fig. 2.

At each quarter rotation of the rotor 4 the position of the valves 13' and 14' is alternated so that the previously uncovered ports supplying steam under full pressure to the high pressure pockets are covered and the other series of passageways uncovered 50 to permit the flow of steam in the opposite direction to supply the next succeeding series of rotor pockets.

While a similar form of valve control mechanism may be utilized upon the opposite end plate 8 of the engine, I prefer to utilize a form of valve which will permit the more rapid operation of the rotor by the provision of instantaneous flow of steam from the steam valve chambers to the high 55 pressure pockets of the rotor, and this may be readily accomplished through the utilization of a form of instantaneously acting steam actuated valves, these having the advantage by moving more quickly and of supplying steam more rapidly and for a

longer period of time at high pressure than is possible to obtain by the form of D valve utilized on plate 7. Therefore for ordinary driving purposes when greater power is obtained the valve 23 of the branch pipe 22 from the main 20 is closed and steam is directed through branch pipe 22 which is provided with a valve 23^a connected to a suitable system of branch pipes illustrated in Fig. 2 as at 24'. These branch pipes lead respectively into upper and lower steam chests 25 and 25'. In each of these steam chests there is arranged a piston or bobbin valve 26 and 26' shown in Fig. 2. As these valves are substantially duplicate and operate in steam chests provided with substantially duplicate sets of steam ports and passageways, a description of one of these steam piston valves and its ports or steam passageways will suffice to describe both. 80 As shown in Figs. 7 and 8, the piston valve 26 is reciprocally mounted in its chamber 25 and moves into contact at opposite ends of the chest 25 with suitable end plugs or stops 27. The piston 26 is shown as provided with two suitably spaced peripheral grooves 26^a and 26^b, which in their position at one end or the other of the steam chest 25 are adapted respectively to register with spaced supply ports 28 or 28' which connect with a common passageway 29 to which the adjacent end of the steam feed pipe 24' may be connected. When the piston valve 26 is in the position shown in Figs. 7 and 8, the annular groove or port 26^b registers with a supply port 30 leading into a complementary passageway 31, this in turn opening into one of the side pockets, as 31^a, on the inner face of the end plate 8 so that as the rotor 4 rotates one of the side pockets 12 thereof will be supplied with steam under full pressure, the force of which impinges upon a radial wall of the pocket with force tending to rotate or drive the rotor. Communicating with the passageway 31 there is provided next adjacent to the high pressure passageway or port 30 a passageway 32 which leads angularly through the wall or body structure of the steam chest 25 and is so disposed at its mouth that when the piston 26 is in the position shown in Figs. 7 and 8 the central body portion of the piston covers the passageway 32. Adjacent to the passageway 32 there is provided a similar passageway 32' which connects with a steam passageway 31', this in turn leading in an opposite direction from the passageway 31 so as to supply steam under full pressure to a pocket 31^b. When one of the steam pockets 12 in the adjacent side of the rotor moves into registration with the steam pocket 31^b if there is steam under pressure in the pocket 12, this steam will be permitted to exhaust through the passageways 31' and 32' into the annular 100

grooves 26^a of the piston 26, this groove being, when the piston valve is in the position shown in Figs. 7 and 8, in registration with one of the mouths of an exhaust port 33 which is provided with a duct leading upwardly and outwardly into an adjacent compound pocket 11 as shown in Fig. 2.

Next adjacent the exhaust port 32' there is provided a high pressure port 30' which, with the piston valve 26, shown in its position in Fig. 8, is covered by the end body portion of the valve, and therefore steam pressure cannot pass into the port 30' while the port 32' is maintained in communication with the groove 26^a to effect the exhaust of steam pressure from the pocket 31^b.

The piston valves 26 and 26' are adapted to be each reciprocated alternately through fluid pressure during the cycle of rotation 20 of the rotor 4 so that the valve 26 at one time supplies steam pressure through the port 30 to one of the high or initial pressure pockets in the side wall or to the other of the pockets. To secure the automatic operation of shifting the piston valve from one 25 position to the other suitable ducts are provided, as shown in Figs. 3 and 7, whereby steam under pressure may be conveyed from one of the pockets 12 of the rotor in the adjacent side 8 of the engine to one or the other of the ends of the chamber in the steam chest in which the valve 26, for instance, operates. For that purpose, from the right hand end of the steam chest, shown in Fig. 3, of the valve 26 there is indicated a by-pass port or duct 34 which is directed through the body of the end plate downwardly to a suitable point 35 where it is adapted to be uncovered by one of the upwardly moving 30 pockets 12 in the adjacent side of the rotor, this pocket having previously been supplied with steam from the lower automatic valve 26'. Therefore when steam enters the mouth 35 of the by-pass duct 34 steam will enter the right hand end of the steam chamber 25 of the valve 26 and the pressure reacting on the end of the latter will cause this to be shifted toward the left and thereby cause the high pressure steam port 30 to be 35 covered, the exhaust port 32 to be uncovered, exhaust port 32' to be covered, and the adjacent high pressure port 31' uncovered by registration with the annular groove 26^a so that steam under full pressure from the chamber 29 may pass then to the passage-way 31' and pressure be introduced into the adjacent pocket 12' of the moving rotor. The valve 26 is adapted to be pushed toward the right by the admittance of fluid 40 pressure into the left end of the steam chest 25 through means of a duct or by-pass 34' opening through the end plate 8 of the engine into communication with one of the pockets 12 of the rotor as this latter swings 45 into registry with the mouth of the by-pass

or duct 34 thus obtaining the position of the piston valve 26 shown in Figs. 7 and 8. After the valve 26 is shifted by pressure in 34 or 34', this pressure falls as the rotor pockets pass the wall pockets or may be exhausted to the compounding ports if desired.

From the foregoing it will be seen that steam under high pressure is initially used in the several steam pockets or chambers 75 12 arranged in the end walls or faces of the rotor and by the proper movement of the respective valves the steam is adapted to exhaust after a predetermined movement of the rotor back through the valve or steam 80 chests and thence outwardly through the ports or passageways so as to be expanded or used to impinge upon the abutment walls of the pockets 10 of the rotor 4. That steam which has been expansively used or compounded in the compound pockets 10 of the rotor is adapted to be exhausted through the registration of the pockets 10 of the rotor as these latter move into juxtaposition with suitable exhaust passageways or pipes 6^a 85 90 which may be provided at appropriate positions about the periphery of the casing 6. While the position of the exhaust ports 6^a for permitting the relief of pressure or exhaust of the steam from the compounding 95 pockets 10 of the rotor may be located at suitable points, preferably they are so disposed that after the energy of the steam has been expansively used to a predetermined degree in the pockets 10 these latter as they 100 pass out of coördinate relation with the pockets 11 at the upper and lower portions of the casing 6 will move into registration with the inner ends of the ports 6^a and the steam thereby be exhausted.

By reversing the relative positions of the pockets 12 or 31^b on the opposite sides of the rotor and by reversing the respective positions of the peripheral pockets in the two series formed about the circumference of the rotor, it will be seen that by closing the valve 23^a, for instance, after the engine has been running in a clockwise direction and opening valve 23 steam will be diverted from the main 20 to the opposite side of the 110 rotor, and its admission will be controlled thereto through the actuation of the piston valves 13' and 14' and the rotor be driven in a left hand direction, for instance. If it be desired to entirely stop the engine it is only 115 necessary to open the valves 23 and 23^a simultaneously. The reacting force acting oppositely upon the rotor will cause the latter to slow down and stop. To entirely 120 stop the operation of the engine the valve 21 may be closed or either the valve 23 or 23^a as 125 may have been in use during the operation of the engine.

While I have shown the compounding 130 pockets as arranged peripherally upon the

rotor it is obvious that they may be disposed at any other suitable point or zone about the rotor, and this also may be said of the high pressure pockets in the sides of the rotor.

To prevent loss of pressure between the running joints of the several parts of the engine suitable packing members may be introduced throughout the arrangement of the engine, and in the present organization there is provided at each side of the rotor 4, as shown in Fig. 2, end wall packings 40, the pressure of which may be variously controlled through means of set screws or other suitable devices 41. There is also shown adjacent each edge of the peripheral portion of the rotor 4 annular packings 42, these being disposed in grooves formed in the cylindrical casing 6.

20. What I claim is:

1. In a rotary, fluid-pressure operated motor, a rotor having series of initial pressure and expansion or compounding pockets with impact faces, substantially radial in arrangement on the rotor, a casing having passageways providing for communication in proper sequence, of the initial and expansion pockets, a fluid-pressure supply, and a valve arranged in the casing for controlling admission of fluid to one of the initial or high pressure pockets and concurrently establishing connection between another high pressure pocket and an expansion pocket, and exhaust means for the series of expansion pockets.

2. In a rotary, fluid-pressure operated motor, a rotor having a series of high pressure pockets and a series of low pressure pockets in its surface, said pockets having at one end an impact face substantially radially disposed, a casing in which the rotor is mounted, valves in said casing, a fluid pressure supply, and direct and expansion steam passageways in the casing controlled by said valves, each valve providing for expansion of steam from the initial or high pressure pockets to the expansion pockets, and exhaust means registerable with the expansion pockets to provide for exhaust of pressure therefrom.

3. In a compound rotary motor, a rotor having series of pockets, each pocket having a substantially radial impact face, a casing inclosing the rotor, a source of fluid pressure, and means for controlling the supply of high pressure initially to one series of pockets and concurrently connecting a given high pressure pocket to one of a second series, and means providing for the exhaust of pressure from the latter series.

4. In a compound rotary motor, a rotor having series of pockets with inclined bottom walls, each pocket having a substantially radial impact face, a casing inclosing the rotor, a source of fluid pressure, and

means for controlling the supply of high pressure initially to one series of pockets and concurrently connecting a given high pressure pocket to one of a second series, and means providing for the exhaust of pressure from the latter series.

5. In a compound rotary motor, a rotor having series of pockets with inclined bottom walls, each pocket having a substantially radial impact face, a casing inclosing the rotor, a source of fluid pressure, and means for controlling the supply of high pressure initially to one series of pockets and concurrently connecting a given high pressure pocket to one of a second series, and means providing for the exhaust of pressure from the latter series, the bottoms of said pockets all symmetrically inclining in the coördinate series and terminating at their inner and deeper ends at the roots of their respective impact faces.

6. In a compound rotary motor, a rotor having series of pockets, each pocket having a substantially radial impact face, a casing inclosing the rotor, a source of fluid pressure, and means for controlling the supply of high pressure initially to one series of pockets and concurrently connecting a given high pressure pocket to one of a second series, and means providing for the exhaust of pressure from the latter series, the impact faces of coördinate series all being symmetrically disposed.

7. In a compound rotary motor, a rotor having series of pockets, each pocket having a substantially radial impact face, a casing inclosing the rotor, a source of fluid pressure, and valves for controlling the supply of high pressure initially to one series of pockets and concurrently connecting a given high pressure pocket to one of a second series, and means providing for the exhaust of pressure from the latter series.

8. In a compound rotary motor, a casing, a rotor mounted therein, a supply for fluid pressure, a series of passageways for high pressure leading to the rotor, a passageway leading to a compounding pocket in the rotor, and a valve movable alternately to permit supply of high pressure to one or another of said high pressure passageways and concurrently connecting the other high pressure passageway to the compounding passageway.

9. In a reversible rotary motor, a casing, fluid pressure supply means connected thereto, a rotor in said casing having series of impact or pressure receiving faces, the faces of one series directed oppositely to those of the other, valve controlled passageways for each series of faces in the rotor, and manually operable control valves in the supply means for selectively directing fluid pressure to one or the other of the said passageways to control the direction of rotation.

10. In a reversible, compound rotary motor, a casing, a rotor in said casing having a set of series of impact faces symmetrically facing one direction on the rotor, another set of series of faces symmetrically facing and disposed to face oppositely to those of the other set, whereby pressure applied to one set causes rotation in a direction reverse to that applied to the other set, a supply for fluid pressure, a valvular control means for each set of faces on the rotor, manually operable valves for controlling passage of fluid to said means to determine direction of rotation of the rotor, each set including high and low pressure impact faces, and exhaust means for the low pressure faces.
11. In a motor, a casing having high and low pressure chambers, a rotor mounted in said casing and having impact faces disposed so as to be subjected to pressure of fluid in said chambers, chests each having a high pressure compartment connectible to supply means, a double ported duct in each chest leading to a respective low pressure chamber, high pressure ports leading from each chest to respective high pressure chambers, return ports from said chambers, and a valve in each chest for alternately connecting said return ports and the low pressure duct and concurrently connecting one of the high pressure ports with said compartment, and passageways in the casing for supplying fluid pressure from the rotor to actuate the valves.
12. In a motor, a casing, a rotor mounted therein, a valve chest having a live or high

pressure chamber, a double ported, compound duct in said chest, sets of high pressure and return ports leading to and from a high pressure chamber in the casing, and a valve in the chest having port-ways registrable alternately with respective high and return ports of said sets, and alternately with the ports of the compound duct.

13. In a motor, a casing, a rotor mounted therein, a valve chest having a live or high pressure chamber, a double ported, compound duct in said chest, sets of high pressure and return ports leading to and from a high pressure chamber in the casing, and a fluid pressure operated valve in the chest having port-ways registrable alternately with respective high and return ports of said sets, and alternately with the ports of the compound duct.

14. In a motor, a casing having high and low pressure chambers, a rotor mounted in said casing and having impact faces disposed so as to be subjected to pressure of fluid in said chambers, chests each having a high pressure compartment connectible to supply means, a double ported duct in each chest leading to a respective low pressure chamber, high pressure ports leading from each chest to respective high pressure chambers, return ports from said chambers, and a valve in each chest for alternately connecting said return ports and the low pressure duct and concurrently connecting one of the high pressure ports with said compartment.

In testimony whereof I affix my signature.
RICHARD CLAYTON FRASER.
